UNITED STATES PATENT OFFICE.

MAURICE J. SCHLESS, OF NEW YORK, N. Y.

DESIGN FOR A DISPLAY TRAY.

Application filed May 31, 1922. Serial No. 2,474. Term of patent 7 years.

To all whom it may concern:

Be it known that I, MAURICE J. SCHLESS, a citizen of the United States, residing at New York city, in the county of New York and State of New York, have invented a new, original, and ornamental Design for Display Trays, of which the following specification, reference being had to the accompanying drawing, forming a part thereof.

The figure is a perspective view of a display tray showing my new design.

I claim:

The ornamental design for a display tray, as shown.

In testimony whereof I have affixed my signature.

MAURICE J. SCHLESS.

Witnesses:

HARRIET FRIEDMAN,
BESSIE HOBADOFF.
